UNITED STATES PATENT OFFICE.

EDWARD M. SENFTLE AND FRANK ECKERT, OF BUFFALO, NEW YORK.

DOOR CLOSURE FOR RAILWAY CARS.

Application filed May 21, 1925. Serial No. 31,748.

This invention relates to a door closure for railway cars and more particularly to a railway car which is intended to carry grain or other loose or bulk freight as well as 5 package freight and similar goods which do not have a flowing action.

One of the objects of this invention is to provide a door closure for this purpose which will permit of tightly closing the 10 doorway so as to positively prevent leakage of grain or similar materials through the doorway.

Another object of this invention is to so construct the closure that the same does not 15 obstruct the interior of the car body and thereby permits of utilizing the maximum carrying capacity of the same. A further object of this invention is to so mount the door on the car body that the door can be 20 passed inwardly and outwardly through the doorway and permit of utilizing the same either on the inside of the car or on the outer side of the same in accordance with the character of the freight which is being carried.

25 A still further object of this invention is to so design the closure that the doorway can be either completely closed, or the same may be opened more or less at the top for filling the interior of the car body with grain 30 or similar material, or the lower end of the doorway may be opened more or less for the purpose of discharging the cargo of grain or similar material therefrom.

35 Additional objects of this invention are to so organize this closure and the means of movably mounting the same on the car body that the operation of opening and closing the doorway can be effected easily and conveniently and also permit of manufacturing 40 the same at a cost which will make the same commercially practical.

In the accompanying drawings:—

45 Fig. 1 is a perspective view of one side of a box car showing the same equipped with our improved doorway closure and showing the parts in position in which the doorway is closed completely.

50 Fig. 2 is a horizontal section taken on line 2—2, Fig. 4, but showing the door in a position in which the same is being passed through the doorway.

55 Fig. 3 is a vertical transverse section taken on the correspondingly numbered line in Fig. 1.

55 Fig. 4 is a view similar to Fig. 3 but showing the upper section of the door low-

ered for the purpose of providing ventilation in the interior of the car or permitting grain or similar material to be loaded into the same.

60 Fig. 5 is a similar view showing the lower section of the door raised for the purpose of opening the lower end of the doorway and permitting the escape of grain or similar free flowing material from the interior 65 of the car body.

70 Fig. 6 is a horizontal section taken on line 6—6, Fig. 4, and showing the door in its operative position across the inner side of the doorway.

75 Fig. 7 is a similar view but showing the door moved to the outer side of the car and shifted to one side of the doorway for the purpose of leaving the latter entirely unobstructed and enabling the car to be freely loaded and unloaded.

80 Fig. 8 is a fragmentary horizontal section, on an enlarged scale taken on line 8—8, Fig. 3.

85 Fig. 9 is a fragmentary vertical longitudinal section taken on line 9—9, Fig. 2.

90 Fig. 10 is a fragmentary horizontal section on an enlarged scale, taken on line 10—10, Fig. 1.

95 Similar characters of reference indicate 85 like parts throughout the several views.

The body of the railway car shown in the drawings is an example of one adapted for use in connection with our invention and comprises a lower bottom 11, an upper roof 12 and a longitudinal side wall 13 which is provided with a doorway 14 through which the freight or cargo to be transported is introduced into the car body and removed 95 therefrom.

100 On its opposite vertical sides or edges this doorway is provided with vertical flanges 15 which project inwardly therefrom and which are preferably constructed of metal and secured to the adjacent surfaces of the doorway by means of screws 16 or any other suitable manner.

105 On the bottom or threshold of the doorway the same is provided with an outwardly facing rabbet 17.

110 In the preferred construction the door proper consists of two sheet metal sections, a lower section 18 which is normally adapted to close the lower part of the doorway and an upper section 19 which is adapted to close the upper part of the doorway, this lower section being preferably arranged on

the inner side and the upper section 19 on the outer side with reference to the doorway. These two door sections are capable of sliding vertically with reference to each other so that they can be either extended vertically for the purpose of covering the entire doorway, as shown in Figs. 1 and 3, or the lower door section may be left in its lowered position and the upper section moved downwardly for the purpose of providing an opening in the upper part of the doorway through which grain may be introduced into the car or the interior of the same ventilated, as shown in Fig. 4, or the upper section may be left in its used position and the lower section raised, as shown in Fig. 5 for the purpose of opening the lower part of the doorway and permitting grain or like cargoes to escape. When the lower door section is in its lowermost position the same engages with the rabbet 17 on the threshold of the doorway so as to form a tight joint therewith which will prevent grain or similar material from leaking outwardly at this point. In order to provide a large bearing surface for the lower door section against the rabbet and also to stiffen and strengthen the same, this end is provided with a horizontal outwardly projecting flange 20 which engages with the threshold over a considerable area and thereby further reduces any liability of the cargo leaking out of the interior of the car at this point. On its opposite vertical edges the lower door section is provided with vertical outwardly projecting sealing flanges 21 which are adapted to engage behind the inwardly projecting flanges 15 of the doorway and form a tight joint therewith whereby leakage of grain or similar material between the lower door section and the car body is positively prevented at this point. In the operative position of the lower car door section its opposite vertical edges engage with the inner edges of the flanges 15 and this together with the flanges 21 on the door engaging behind the vertical flanges 15 and the lower flanged end on the lower car door section engaging with the rabbet 17 produces a water tight joint between the lower door section and the car body which effectively excludes the entrance of water, dust and dirt from the exterior of the car when the latter is exposed to rain and blowing dust.

Although any suitable means may be provided for connecting the upper and lower door sections so that the same are slidable one upon the other, those shown in the drawings have been found satisfactory in practise and consist of two bolts 22 which pass through an opening on the upper door section and through a vertical slot 23 on the adjacent part of the lower door section and bears with the shoulders at its opposite ends

against the upper side of the upper door section and the inner side of the lower door section, as shown in Figs. 1 to 5.

On the upper parts of the vertical edges of the upper door section the same is provided with outwardly offset portions 24 which in the elevated position of this door section engage with the outer sides of flanges 25 arranged on the upper portions of the inner edges of the transverse flanges 15 and project therefrom in a direction lengthwise of the car and toward each other, as shown in Figs. 2, 3, 4, 5 and 8, thereby forming a weather tight joint between the upper door section and the doorway which will effectively exclude rain and dust which may drive against the closure from the exterior of the car and thereby protect the cargo within the same.

Various means may be provided for moving the two door sections vertically one relatively to the other, those shown in the drawings being preferred and consisting of a gear rack 26 arranged on the outer side of the door sections and secured on its upper end with the upper door section, and a gear pinion 27 pivotally mounted on the lower door section and meshing with the gear rack so that upon turning this pinion one of the door sections will be moved vertically relatively to the other.

The gear rack is preferably guided in a guideway 28 and the gear pinion 27 is mounted on a shaft 29 which is journaled in suitable bearings on a supporting bracket 30 and provided on its front end with a hand wheel 31 for manipulating the same when the lower door section is at its lowered position and resting against the threshold of the doorway and the upper door section is also lowered, as shown in Fig. 4, the latter may be raised for fully closing the doorway by turning the hand wheel 31 in the direction of the arrow associated therewith in Fig. 1. If it is desired to raise the lower door section this is accomplished by turning the hand wheel in a direction opposite to the indication of the arrow in Fig. 1. Inasmuch, however, as the lower door section in the present case is of considerably larger areas and, therefore, heavier it is necessary to provide means for holding the upper door section against vertical movement at this time. This is preferably accomplished by providing the upper door section with horizontally movable locking bolts 32 which are adapted to project in opposite directions from the ends thereof into locking openings 33 in the adjacent vertical edge portions of the doorway, as shown in Fig. 10. These means for locking the upper door section against vertical motion are preferably so arranged that the upper door section is only locked in its uppermost position inasmuch as there is no need for raising the lower

door section at any other time, although if desired additional locking openings 33 may be provided on the doorway below the one which would retain the upper door section 5 in its uppermost position. From the foregoing it will be seen that the same shifting mechanism is utilized for either raising the lower door section or lowering the upper door section, this being possible by holding 10 one door section while the other is free to move and turning the gear pinion 27 in the required direction.

For the purpose of locking the door sections in whatever position they may be left 15 means are provided which in the present instance comprises a horizontally slidable locking bolt 34 adapted to engage with one or another of the teeth of the gear pinion 27 and sliding in a guideway 35 on the outer 20 side of the lower door section and provided with a handle 36 for manipulating the same, as best shown in Figs. 1, 2 and 9. If it is desired to seal the car after it is closed this may be accomplished by means of a 25 sealing bolt 37 guided on the lower door section by means of a bolt 38 on this door section passing through a slot 39 on the upper part of this bolt, and the lower end of this sealing bolt passing through an opening 30 in the locking bolt 34 and adapted to receive a wire seal 40 such as are now commonly employed for preventing a lock from being opened by unauthorized parties without detection. Upon removing the seal 40 35 the sealing bolt may be raised thereby liberating the locking bolt 34 and permitting the gear mechanism to be operated for sliding the door sections vertically one relatively to the other for unloading the cargo. 40 Means are provided for moving the car door inwardly and outwardly through the doorway so as to permit the door to either extend across the doorway on the inner side 45 of the car body or to extend across the doorway on the outer side of the car body and also to permit the door to be moved bodily to one side of the doorway on the outer side of the car body when it is desired to leave the doorway completely unobstructed 50 for loading or unloading the same with package freight or similar commodities. The preferred means for thus mounting the door shown in the drawings are constructed as follows:—

55 Slidable horizontally and lengthwise of the car on the outer side of the side wall 13 is a carriage which preferably has the form of a rectangular frame which comprises upper and lower horizontal bars 41, 42 arranged adjacent to the upper and lower edges of the doorway, and two upright bars 43 connecting the corresponding ends of the upper and lower bars 41, 42 and adapted to be arranged adjacent to the vertical edges 60 of the doorway when the door is closed.

This carriage may be movably supported in any approved manner, the means for this purpose shown in the drawings as an example consisting of rollers 44 arranged in the lower bar 42 of the carriage which is made 70 hollow or of channel shaped form in cross section for this purpose and running on a horizontal track or rail 45 secured to the adjacent lower portion of the car body, as shown in Figs. 3, 4 and 5, and the upper bar 75 of the carriage being provided with upwardly projecting guide lugs 46 which engage with a slotted guide bar 47 secured to the body of the car above the door opening, as shown in Figs. 1, 3, 4 and 5. 80

Arranged vertically adjacent to the outer sides of the two upright bars 43 of the frame shaped carriage are two upright supporting and guide rods 48 which may be held in place on this carriage in any suitable 85 manner, for instance by means of brackets 49, 50 and 51 which receive the upper, intermediate and lower parts of each of these guide rods and are secured to the adjacent parts of the carriage, as best shown in Figs. 90 1-5. Adjacent to the vertical edges of the door the outer side of the same is connected with the guiding and supporting rods 48 by means of toggles which are so constructed that the door may be tilted in such a position 95 relatively to the carriage and doorway so as to be capable of passing through the doorway either inwardly or outwardly, as shown in Fig. 2 and also permit the door to be arranged parallel with the side wall of the car 100 body and extended across the inner side of the doorway, as shown in Fig. 6 and also enable the door to be arranged in a position parallel with the side wall of the car body and either remain in a position extending 105 across the outer side of the doorway, or to be shifted into a position on one side of the doorway, as shown in Fig. 7. In the preferred construction the door is supported adjacent to each of its vertical edges on one 110 of the supporting rods by means of two toggles and these toggles are preferably connected only with the lower door section so that the upper door section is supported indirectly upon the supporting and guide rods 115 48. Each of these toggles consist of a pair of links consisting of an outer link 52 and an inner link 53, the opposing ends of which are pivotally connected to each other by 120 means of a vertical pintle 54 and the outer extremity of the outer link 52 being mounted on the adjacent guide rod 48 so as to be free to turn thereon and also to slide vertically relatively thereto while the inner link 53 is 125 pivotally connected at its inner extremity by means of a vertical pivot pin 55 on the brackets 56 on the adjacent part of the outer side of the lower door section. When the car door is in its inner operative position 130 across the inner side of the doorway,

as shown in Fig. 6 the inner link of each pair of toggles is arranged in a position transversely of the length of the car and the outer links incline inwardly, but when the car door is on the outer side of the car body, as shown in Fig. 7, the inner links are also arranged transversely but the outer links are inclined outwardly. When it is desired to pass the door either inwardly or outwardly through the doorway the links of the several toggles are so manipulated that the door as a whole is held or shifted into an angular position horizontally relative to the door opening so as to permit of passing the same endwise through the door opening, this being necessary owing to the fact that the width of the door is greater than the width of the doorway. The manner in which this is accomplished is shown in Fig. 2 in which the toggle at the left hand of the door is extended or unfolded to a greater extent and the links of the toggle at the right hand end of the door is doubled or folded upon itself to a relatively greater extent, thereby adapting the position of the links of the toggles to the required position in order to enable the door to be canted or assume such an angular position as will permit the same to be passed either inwardly or outwardly through the doorway preparatory to again sliding the door into a position in which the same is arranged lengthwise of the car for either engaging the same with the inner side of the door way or arranging the same in a corresponding position on the outer side of the doorway.

Means are provided for lifting the door bodily so that the lower edge of the lower door section will be clear of the threshold and thereby enable the door to be moved freely into and out of the car without dragging over the threshold and also to sustain the door in this position when the same is outside of the car and being moved lengthwise along the side wall thereof. Means for this purpose preferably comprise two adjusting screw nuts 57 arranged on the lower screw threaded parts of the supporting rods 48 and two spacing or supporting sleeves 58 each surrounding the lower part of one of the supporting rods 48 and bearing with its lower end against the respective screw nut 57 while its upper end engages with the under side of the outer link 52 of the adjacent toggle, as shown in Figs. 1, 3, 4 and 5. When it is desired to lift the door sufficiently to disengage the lower end of the lower door section from the threshold in the doorway the screw nuts 57 are turned in the proper direction for causing the same to move upwardly which movement is transmitted successively by the supporting sleeves 58 and lower toggles through the lower door section and parts mounted thereon whereby the door will be maintained in this position

at the time when the same is moved into and out of the car and also while the same is being moved lengthwise of the car on the outer side thereof. After the door has been moved inwardly through the doorway and assumed its proper parallel position across the inner side of the doorway and in engagement with the sealing flanges 15, 15, then the screw nuts 57 are turned in the reverse direction and cause the same to descend and thereby permit the lower door section to drop by gravity and engage its lower edge with the rabbet 17 of the threshold and form the tight joint therewith.

When moving the carriage lengthwise of the car body into a position in which the same stands in front of the doorway where the door can be moved inwardly and outwardly through the doorway the movement of the carriage in this direction is limited by means of a stop 60 which is secured to the adjacent part of the side wall 13 in position to be engaged by the front end of the carriage, as shown in Figs. 2 and 6.

When the door is moved outwardly beyond the outer side of the car side wall 13 and into a position for moving lengthwise of this wall with the carriage, the outwardly projecting flanges 21 on the door engage with inwardly projecting flanges 59 on the carriage, as shown in Fig. 7, thereby holding the carriage and door against movement lengthwise relatively to each other at this time and compelling the same to move in this direction as a unit.

From the foregoing it will now be clear that this construction of car door and the manner of mounting it on the car body and manipulating the same for opening or closing the doorway wholly, or partly opening the same either at the top or the bottom is reliable and effective in its operation and not only permits of securely closing the car so as to render the same leak-proof but also permits of readily loading and unloading a car either with a cargo of loose material such as grain, package or similar material. This can be accomplished without liability of destroying or injuring any of the parts or necessitating frequent renewals or reparments as has been the custom heretofore thereby effecting a considerable economy in the operation and maintenance of car doors when shipping materials of this character.

We claim as our invention:

1. A closure for a railway car having a doorway, comprising a carriage mounted for lengthwise movement on the exterior of the car, a door for closing said doorway, and means for mounting said door on said carriage and constructed to permit of moving said door inwardly and outwardly through said doorway and pressing said door outwardly against the inner side of the car wall.

2. A closure for a railway car having a

- doorway, comprising a carriage mounted for lengthwise movement on the exterior of the car, a door for closing said doorway, and means including a plurality of toggles for 5 mounting said door on said carriage and constructed to permit of moving said door inwardly and outwardly through said doorway and pressing said door outwardly against the inner side of the car wall.
- 10 3. A closure for a railway car having a doorway, comprising a carriage mounted for lengthwise movement on the exterior of the car, a door for closing said doorway, and means for mounting said door on said carriage and constructed to permit of moving 15 said door inwardly and outwardly through said doorway and pressing said door outwardly against the inner side of the car wall comprising supports arranged on said carriage at opposite ends thereof, and a plurality of toggles each having a pair of links which have their opposing ends pivotally connected with each other and their extremities pivotally connected with said door and 20 said supports.
4. A closure for a railway car having a doorway, comprising a carriage mounted for lengthwise movement on the exterior of the car, a door for closing said doorway, and 25 means for mounting said door on said carriage and constructed to permit of moving said door inwardly and outwardly through said doorway and pressing said door outwardly against the inner side of the car wall comprising upright pivot rods arranged at 30 opposite ends of said carriage, and a plurality of toggles each consisting of a pair of links which are pivotally connected with each other and the outer member of each 35 pair being capable of turning and sliding on one of said rods and the inner member of each pair being pivoted on the adjacent end of the door.
5. A closure for a railway car having a 40 doorway, comprising a carriage mounted for lengthwise movement on the exterior of the car, a door for closing said doorway, and means for mounting said door on said carriage and constructed to permit of moving 45 said door inwardly and outwardly through said doorway comprising upright pivot rods arranged at opposite ends of said carriage, and a plurality of toggles each consisting of a pair of links which are pivotally connected with each other and the outer member of each 50 pair being capable of turning and sliding on one of said rods and the inner member of each pair being pivoted on the adjacent end of the door.
- 55 6. A closure for a railway car having a doorway, comprising a carriage mounted for lengthwise movement on the exterior of the car, a door for closing said doorway, and means for supporting the door in various vertical positions 60 relatively to said carriage.
- 65 7. A closure for a railway car having a doorway, comprising vertical flanges arranged at opposite vertical edges of the doorway and projecting inwardly therefrom, a carriage mounted for lengthwise movement on the exterior of the car, a door having outwardly projecting vertical flanges at its opposite vertical edges adapted to engage behind said flanges of the doorway, and means for mounting said door on said carriage so as to permit the same to move through said doorway.
8. A closure for a railway car having a doorway, comprising vertical flanges arranged at opposite vertical edges of the doorway and projecting inwardly therefrom and an outwardly facing rabbet on the threshold of said doorway, a door adapted to engage its lower end with said rabbet and provided at its opposite vertical edges with outwardly projecting flanges adapted to engage behind said flanges on the doorway, a carriage mounted for lengthwise movement on the exterior of the car, and means for mounting said door on said car which permit said door to move inwardly and outwardly through said doorway and also enable said door to move toward and from said rabbet.
9. A closure for a railway car having a doorway, comprising a door adapted to engage with the inner side of the car, a frame shaped carriage which is mounted on the exterior of the car so as to be capable of longitudinal movement thereon, and means for mounting said door on said carriage.
10. A carriage for a railway car having a doorway, a door having upper and lower sections which are slidable vertically relatively to each other, a carriage mounted for longitudinal movement on the exterior of the car, and means for movably mounting said door on said carriage.
11. A carriage for a railway car having a doorway, a door having upper and lower sections which are slidable vertically relatively to each other, a carriage mounted for

- longitudinal movement on the exterior of the car, means for movably mounting said door on said carriage, a gear rack on one of said door sections, and a gear pinion 5 mounted on the other door section and meshing with said rack.
12. A carriage for a railway car having a doorway, a door having upper and lower sections which are slidable vertically relatively to each other, a carriage mounted for longitudinal movement on the exterior of the car, means for movably mounting said door on said carriage, and means for locking said sections against vertical movement.
13. A closure for a railway car having a doorway, comprising a frame shaped carriage mounted for longitudinal movement on the exterior of said car, a door having upper and lower sections which are slidable 10 vertically relatively to each other, means for mounting one of said door sections for vertical movement on said carriage, and means for locking the other door section against vertical movement relative to said car.
14. A closure for a railway car having a doorway, comprising a frame shaped carriage mounted for longitudinal movement on the exterior of said car, a door having upper and lower sections which are slidable 15 vertically relatively to each other, means for mounting one of said door sections for vertical movement on said carriage, and means for locking the other door section against vertical movement relative to said car.
15. A closure for a railway car having a doorway, comprising a frame shaped carriage mounted for longitudinal movement on the exterior of said car, a door having upper and lower sections which are slidable 20 vertically relatively to each other, means for mounting one of said door sections for vertical movement on said carriage, and means for locking the other door section against vertical movement relative to said car.
16. A closure for a railway car having a doorway, comprising a frame shaped carriage mounted for longitudinal movement on the exterior of said car, and a door adapted to extend across said doorway and mounted on said carriage for vertical movement thereon.
17. A closure for a railway car having a doorway, comprising vertical transverse flanges arranged at opposite vertical sides of the doorway, vertical longitudinal flanges 25 arranged on the upper parts of said transverse flanges and projecting toward each other, and a door having a lower section adapted to engage with the inner sides of said transverse flanges and an upper section adapted to engage with the outer side of said longitudinal flanges.
18. A closure for a railway car having a doorway, comprising vertical transverse flanges arranged at opposite vertical sides 30 of the doorway, vertical longitudinal flanges arranged on the upper parts of said transverse flanges and projecting toward each other, a door having a lower section adapted to engage with the inner sides of said transverse flanges and an upper section adapted to engage with the outer side of said longitudinal flanges, a carriage mounted on the exterior of the car for longitudinal movement thereon, and means for connecting said door with said frame and permitting the same to be moved through said doorway.

In testimony whereof we affix our signatures.

EDWARD M. SENFTLE.
FRANK ECKERT.
